UNITED STATES PATENT OFFICE.

RICHARD ALVIN BREUL, OF BRIDGEPORT, CONNECTICUT.

MITER-SQUARE.

SPECIFICATION forming part of Letters Patent No. 768,324, dated August 23, 1904.

Application filed December 29, 1903. Serial No. 187,004. (No model.)

To all whom it may concern:

Be it known that I, RICHARD ALVIN BREUL, a citizen of the United States, and a resident of Bridgeport, in the county of Fairfield and 5 State of Connecticut, have invented certain new and useful Improvements in Miter-Squares, of which the following is a specification.

This invention relates to new and useful improvements in miter-squares such as shown in patent to Fox, No. 331,047, and is likewise equally as well adapted to try-squares and various forms of other squares and bench-tools.

It is the object of the invention to improve 15 upon squares of the above classes by materially stiffening the back, and especially the face of the back, where injury is most liable and likewise most objectionable, at the same time to lighten and improve the appearance 20 of the back.

The Fox square referred to is shown formed of two parts, the back of which is unnecessarily heavy, besides having sharp prominent corners, which readily become bruised by 25 rough usage. There are also other forms of squares wherein the backs are made of sheet metal, one edge being turned out at right angles to form a face. Practically these tools are not stiff enough to prevent the face of the 30 back from being dented or bent by use, thus rendering them also unreliable.

With the above features in mind my invention resides and consists in the novel construction and combination of parts shown upon the 35 accompanying sheet of drawings, forming a part of this specification, upon which similar characters of reference denote like or corresponding parts throughout the several figures, and of which—

Figure 1 shows a perspective view of my improved miter-square complete. Fig. 2 is a rear edge view of the same. Fig. 3 is a detailed perspective view of the beam member of the back. Fig. 4 is a central vertical cross-section taken on lines 4-4 through the back of the square, showing the construction of the same. Fig. 5 shows a side elevation of a try-square embodying my improvement, and Fig. 6 shows a cross-section of a slightly-modified 50 form of back.

My improvement is practically made of

three parts, each being formed of sheet metal stamped out and bent to conform to the respective shapes required, then assembled and secured together, producing a square of the 55 greatest possible strength where required and consistent with a given weight of material.

Referring in detail to the characters of reference marked upon the drawings, A represents the blade of the square, which comprises a vertical angular member B and C, respectively, the latter being arranged at an angle of forty-five degrees to the vertical member, while the vertical member is arranged at a right angle to the back or beam. Both of 60 these members of this blade may be provided with suitable graduations, if desired, and laid out in any given number of equal parts.

The back referred to consists of two pieces of sheet metal D and E. The former is preferably bent up into a U-shape beam with its upper edges turned out at right angles forming flanges F. The bottom of this beam is cut away at one end, as at K, to receive the inner edge of the vertical section B of the 75 blade and is secured in any suitable way—as, for instance, by means of a rivet—while the outer end is in a like manner secured to the member C, thus holding the beam and the vertical member at right angles in respect to each 80 other.

If desired, this square can be used as a try-square; but when miter-lines of forty-five degrees are desired they are struck along either 85 edge of the member C.

E represents a face-plate which lays across the top of the flanges F of the beam and secured thereto by having its outer edges H turn snugly in under said flanges. The central portion of each end of this face-plate is 90 cut away, as are I and J, to receive the inner edges of the members B and C, thus extending the face of the back along the sides of said members of the square in a way to insure ample engagement of the back with work. 95

The specially-constructed back in question obviously comprises the features of my square and has the advantages of being light, neat in appearance, and exceptionally strong, being formed of three thicknesses of sheet-steel, and thus affords ample resistance to such rough usage as it is liable to get. 100

In Fig. 5 of the drawings I have shown a try-square the back of which is constructed in substantially the same manner as that referred to in the miter-square, which figure 5 shows that my invention is equally applicable to try-squares and, in fact, can also be employed upon other forms of bench-tools.

It is further apparent that should it be desired to form a back for either the miter or 10 try-square with a face on both its inner and outer edge the same could be accomplished in substantially the same way by employing two channel-beams D' to take the place of the U-shape beam before mentioned and in which 15 instance two face-plates E' would be used to cover the upper and lower faces of the flanges F' of the beam, thus producing a construction which is in all essentials practically like that of the above-described construction and likewise 20 justly comes within the scope of my invention.

Having thus described my invention, what I claim, and desire to secure by Letters Patent, is—

25 1. In a square of the class described, the combination with a blade, of a back formed of sheet metal, and comprising a beam bearing longitudinal and outwardly-disposed flanges, and a face-plate covering and attached to the 30 flanges of said beam.

2. In a square of the class described, the combination with a blade member, of a back attached thereto comprising a beam bearing flanges disposed outwardly in opposite directions along its upper edge, and a face-plate covering the face of said flanges and having its edges turned over and bent under the edges of 35 said flanges.

3. In a square of the class described, the combination with a blade member, of a back 40 comprising a U-shaped beam having its upper edges turned outward in opposite directions at substantially right angles and a face-plate secured to the top face of said flanges in a way to secure the same to the edges of said flanges. 45

4. In a square of the class described, the combination with a blade member, of a back comprising one or more beams, the edges of which are disposed outward at substantially right angles, and parallel with each other, and 50 plate covering such edges of such flanges in a way to protect and reinforce the same substantially as described.

Signed at Bridgeport, in the county of Fairfield and State of Connecticut, this 21st day of 55 December, A. D. 1903.

RICHARD ALVIN BREUL.
